ENVELOPE OPENER

Louis A. Deicken, San Francisco, Calif.

Application September 21, 1954, Serial No. 32,372

Term of patent 14 years

(Cl. D74—11)

Fig. 1.

Fig. 3.

Fig. 4.

Fig. 2.

Fig. 5.

Fig. 6.

Figure 1 is a top plan view of an envelope opener, showing my new design;

Figure 2 is a front elevational view thereof;

Figures 3 and 4 are elevational views as seen from the opposing ends of the envelope opener, as indicated by the lines III—III and IV—IV, respectively, in Figure 2;

Figure 5 is a rear elevational view of the envelope opener; and

Figure 6 is a bottom plan view.

I claim:

The ornamental design for an envelope opener, substantially as shown.
